UNITED STATES PATENT OFFICE.

EMILE GIRAUD, OF PARIS, FRANCE.

INSULATOR FOR HIGH-TENSION LINES.

No. 820,924.

Specification of Letters Patent.

Patented May 15, 1906.

Original application filed October 31, 1903, Serial No. 179,376. Divided and this application filed October 1, 1904. Serial No. 226,795.

To all whom it may concern:

Be it known that I, EMILE GIRAUD, engineer, a citizen of the Republic of France, residing at Paris, 18 Rue Royale, in the Republic of France, have invented a new and useful Improvement in Insulators for High-Tension Lines, of which the following is a specification.

This invention is a divisional application of Serial No. 179,376, dated October 31, 1903, and relates to an insulating apparatus intended for high-tension lines and so arranged or fitted up as to automatically put the line-wire in communication with a discharge or return conductor when the said wire is broken at any point in order that the falling portions of the falling wire shall not be dangerous. In the said apparatus a socket is fixed on a porcelain head or bell, and through which is free to slide a tube fixed onto the line-wire. On the ends of the socket are pivoted contact-arms, the ends of which are adapted to meet a discharge-conductor. On the other hand, the ends of the tube on the wire carry members which engage with the said arms and cause the same to swing when the wire is displaced to one side or the other—that is, when the wire is broken. In this swinging motion one of the arms meets with the discharge conductor, so that the portion of the line-wire leading to the insulating apparatus is discharged of the dangerous current through the said arm and the said conductor.

In the accompanying drawings, Figure 1 is an elevation of an apparatus shown in the position of rest, and Fig. 2 is a corresponding plan view showing in dotted lines an operative position of the same.

The head 15 of the insulator is stationary and carries a socket 22, which is stationary also and in which a split tube 23 is freely slideable. The line-wire 8 is fixed in the tube 23 and clamped therein by clips 24, located on the said tube and which are passed through by bolts 25. On the ends of the socket 22 are fixed clips 26, provided with pivots 27, around which are free to rock rods 28, which extend outward on each side and pass freely through eyes 29, formed on the clips 24. Each rod 28 is provided with an arched part 30, in such a manner that when the tube 23 moves longitudinally, the eye 29, sliding on the said arched part, causes the rod 28 to move round the fixed pivot 27, as shown in dotted lines in

Fig. 2. The rod 28 may be bent at right angles at its free end so as to meet in thus turning round a conducting-wire (not shown) arranged parallel to the line-wire 8 or another conductor suitably arranged. The said discharge-conductor may be put in any position, for the socket 22 with the arms 28 can at will be set in such a direction that the said arms will swing in a plane which is more or less inclined.

I claim—

1. An insulating apparatus for high-tension lines, comprising a fixed insulating-head, a socket fixed on the said head, arms pivoted to the socket, a tube adapted to be fixed on the line-wire, members on the said tube to engage with the said arms, and a discharge-conductor so arranged as to be met by the said arms.

2. An insulating apparatus for high-tension lines, comprising a fixed insulating-head, a socket fixed on the head, arms pivoted to the socket and having a curved part and a bent end, a tube slideable in the socket, eyed members on the said tube and through which the arms pass, and a discharge-conductor so arranged as to be met by the bent end of the said arms.

3. An insulating apparatus for high-tension lines, comprising a fixed insulating-head having a socket, a tube slidably mounted in the socket, means for securing the tube to the line-wire, arms pivoted to the socket and normally lying substantially parallel therewith, and means whereby the movement of the tube through the socket may swing the arm transversely thereof.

4. An insulating apparatus for high-tension lines, comprising an insulating-head having a socket for receiving the line-wire, arms pivoted to the insulator and normally lying substantially parallel with the line-wire, and connections between the line-wire and the arms whereby the movement of the wire through the socket may swing the arms transversely thereof.

In testimony that I claim the foregoing as my invention I have signed my name in presence of two subscribing witnesses.

EMILE GIRAUD.
